[57] CLAIM

The ornamental design for a dual-opening panel sun roof for automobiles, as shown and described.

DESCRIPTION

FIG. 1 is a perspective view of a dual-opening panel sun roof for automobiles having one window thereof in an open position, illustrating our new design;

FIG. 2 is a top plan view thereof with both windows in closed position;

FIG. 3 is an end-elevational view of FIG. 2.

FIG. 4 is a side-elevational view of FIG. 2;

FIG. 5 is a bottom perspective view of FIG. 1; and

FIG. 6 is a bottom plan view of FIG. 2.
